[57] ABSTRACT

A neck exercising device in the form of a hat with a brim that supports one or more circular tracks in which a ball is free to be rolled around each track. The hat is strapped to the head of the operator and the head is continually moved to cause the ball to roll along the endless track. This head movement will strengthen the neck muscles of the operator. The hat brim may have a plurality of concentric circles, each representing the orbit of a planet in our solar system. The name of the planet as well as its distance from the sun is printed on the hat brim and this can be of an educational value to the person using the device.

FIG. 3

FIG. 4

NECK EXERCISING DEVICE

BACKGROUND OF THE INVENTION

Field of the Invention

The purpose of the neck exercising device is to strengthen the neck muscles. A person who wears the hat must move the head in such a manner as to cause the ball to travel around the endless circular track. At the same time care must be taken that the ball will not jump out of the track accidentally. This will require a controlled movement of the head and neck with the result that the neck muscles will be properly exercised and strengthened.

SUMMARY OF THE INVENTION

An object of my invention is to provide a neck exercising device that is in the shape of a hat that can be strapped to the head of the wearer. The hat has a brim which supports a circular track in which a ball is free to roll. The person can tilt the head and neck to cause the ball to travel around the endless track. The continuous movement of the head and neck must be done in a controlled manner in order to keep the ball rolling around the track while preventing the ball from accidentally jumping out of the track. The controlled movement of the head and neck will exercise and strengthen the neck muscles.

BRIEF DESCRIPTION OF THE DRAWINGS

FIG. 1 is a top plan view of the hat and illustrates the circular track with a ball, representing the earth, being free to roll along the track.

FIG. 2 is a side perspective view of the device shown strapped to the head of a person using the device. The dotted lines indicate the various positions of the head and hat necessary for causing the ball to travel along the circular track.

FIG. 3 is an enlarged transverse section taken through the hat along the line 3-3 of FIG. 1. The endless circular track is supported by the hat brim and the ball in the track is shown in section.

FIG. 4 is a side elevation of FIG. 3 where the hat has been rotated 90° about its vertical axis in order to illustrate the two strap portions that depend from the crown of the hat and these can be buckled together under the chin of the wearer for holding the hat in place on the head.

FIG. 5 is a section through a modified form of the device and illustrates a pair of endless tracks arranged in a concentric manner and supported by the hat brim.

DESCRIPTION OF THE PREFERRED EMBODIMENTS

In carrying out my invention I provide a neck exercising device in the form of a hat indicated generally at A and having a crown 1 and a brim 2. The brim may be of any desired diameter and it has an upturned flange 3 at its outer edge. If desired, the crown 1 of the hat A may be provided with a row of ventilation openings 4 that are preferably arranged near the brim 2 and will permit air to circulate near the person's head when the hat is worn. A pair of straps B1 and B2 hang downwardly from the edge of the crown and are provided with the usual buckle for securing the straps under the chin of the wearer for holding the hat in place on the head as shown in FIG. 2.

A novel feature of the invention lies in the provision of a circular track C that extends around the crown 1 of the hat A and is preferably supported by legs 5 that are secured to the upper surface of the hat brim 2, see especially FIG. 3. The endless track is U-shaped in cross section and it receives a ball D that is free to roll around the track as the hat is tilted into different angular positions. FIG. 2 shows by dotted lines how the wearer of the hat A can sway his head so as to tilt the hat for propelling the ball D along the track. It requires a certain amount of dexterity for the person to move his head for keeping the ball rolling along the track without accidentally causing the ball to jump out of the track. However, if this should happen, the ball D would roll to the edge of the hat brim and be prevented from rolling off from the brim by the circular flange 3, see the dotted position of the ball D on the brim 2 in FIG. 2, where the ball has rolled against the flange 3.

The ball D may represent the planet earth as indicated in FIG. 2, and it is possible to provide data on the upper surface of the hat brim 2 to indicate the names and orbits of the other planets in the solar system, as well as giving the distance in miles these different planets are spaced from the sun, which might be represented by the crown 1 of the hat A. For example, in FIG. 1 the orbits of the planets Venus and Mercury are shown lying within the circular track C which represents the orbit for the earth which is the ball D. Next is the orbit of Mars followed by that of Jupiter, then 30 Saturn, Uranus, Neptune and Pluto. If a child uses the device to exercise his neck muscles, he can also learn the names of these different planets in the solar system as well as the tremendous distances they are removed from the sun.

As already inferred, the main purpose for the device is to cause the wearer of the hat to exercise his neck muscles by causing the ball D to roll along the track C. A game could be played between two or more children or adults, each one wearing the device and seeing how long he can keep the ball D rolling in the track C without jumping out. The winner would of course be the one that keeps the ball rolling in the circular track for the longest period of time. The rotary motion of the head and neck in keeping the ball moving along the track is beneficial to the person having a neck problem or having stiffness of the neck muscles. The device is therefore more than a toy.

A modified form of the invention is illustrated in the sectional view of FIG. 5. In this Figure the hat brim 2 supports not only the circular track C, but also another circular track E that is concentric with the endless track C. Another ball, not shown, and similar to the ball D would travel in the endless track E. In this case the person wearing the hat would have to keep the two balls in the two tracks moving along the tracks without jumping out. Any number of concentric tracks could thus be provided.

It is possible to make the brim 2 smaller in diameter and omit the data on top of the brim that indicates the different planets in the solar system and the number of miles they are removed from the sun. The invention can be used as a therapeutic as well as an amusement device by anyone.

I claim:

1. A device of the type described comprising:
  - a crown to fit over the head;
  - a brim extending from the crown;

- c. a circular track extending around the crown;
  - d. a ball receivable in the track and being movable therealong when the crown is mounted on a person's head and the person tilts and sways his neck and head in a manner to cause the ball to travel along the track;
  - e. the track is U-shaped in cross section; and
  - f. a plurality of legs extend from the brim and support the track in spaced relation from the crown.
2. A device of the type described comprising:
- a. a hemispherical crown to fit over the head;
  - b. a brim extending from the crown with the plane of the brim lying substantially in the plane of the open end of the hemispherical crown, said brim having an upturned circular flange at its outer edge to prevent a ball from falling off from the brim;
  - c. a circular track extending around the crown and

- being spaced therefrom; and
  - d. a plurality of legs extending at right angles from said brim for supporting said track above said brim.
3. The combination as set forth in claim 2: and in which
- a. a second circular track extends around and is concentric to said first mentioned circular track; and
  - b. a plurality of legs extending upwardly from said brim for supporting said second circular track above said brim.
4. The combination as set forth in claim 2: and in which
- a. said hemispherical crown has a plurality of ventilation openings arranged in a circular row and adjacent to said brim.
